UNITED STATES PATENT OFFICE.

LOUIS HURWITZ, OF PHILADELPHIA, PENNSYLVANIA.

DESIGN FOR A WRAPPER FOR CHEWING GUM, CANDY, AND CONFECTIONS.

Application filed June 11, 1924. Serial No. 9,856. Term of patent 3½ years.

To all whom it may concern:

Be it known that I, LOUIS HURWITZ, a citizen of Poland, having resided in the United States one year last past and having declared my intentions of becoming a citizen thereof, residing in the city and county of Philadelphia, State of Pennsylvania, have invented a new, original, and ornamental Design for Wrappers for Chewing Gum, Candy, and Confections, of which the following is a specification, reference being had to the accompanying drawing, forming part thereof.

The figure is a plan view of my novel wrapper, showing my new design.

I claim:—

The ornamental design for a wrapper for chewing gum, candy and confections as shown.

LOUIS HURWITZ.
